UNITED STATES PATENT OFFICE.

THEODORE A. MATHEWS, OF WASHINGTON, PENNSYLVANIA, ASSIGNOR OF FORTY PER CENT TO FRED D. JOHNSON AND W. N. BUTLER, TRUSTEES, BOTH OF WASHINGTON, PENNSYLVANIA.

AIR COMPRESSOR.

Application filed February 8, 1927. Serial No. 166,724.

This invention relates to new and useful improvements in air compressing machines, and has for its primary object to provide an extremely novel and relatively simple but 5 efficient mechanism wherein a large supply of compressed air may be provided, and this without requiring an unusual amount of power in the operating of the mechanism.

A further and most important object is to 10 provide such a device that includes a plurality of air compressor pumps, the pistons of which are actuated to compressing position by the rolling of wheels of a rotating unit over means directly associated with the 15 rods of the piston.

With the foregoing and other objects in view as the nature of the invention will be better understood, the same comprises the 20 novel form, combination and arrangement of parts hereinafter more fully described, shown in the accompanying drawings and claimed.

In the drawing wherein like reference characters indicate corresponding parts 25 through the several views:

Figure 1 is a detail vertical section of my improved air compressing device.

Figure 2 is a top plan view thereof.

Figure 3 is a horizontal section taken substantially upon the line 3—3 of Figure 1, and

Figure 4 is an enlarged fragmentary view partly in cross section disclosing one of the compressing units.

Now having particular reference to the drawings, my air compressor consists of a relatively large capacity air tank 5 within the center of which is a vertical tube 6 through which is extended a rotating shaft 7 suitably journaled within the ends of the tube as indicated in Figure 1. The lower end of this shaft 7 is equipped with a gear 8 in mesh with a gear 9 upon one end of a horizontal power shaft 10 that is operatively connected to the shaft of a suitable engine 11.

Arranged circumferentially around the tank 5 in spaced concentric relation therewith and adjacent the upper end thereof is a flanged wheel track 12 formed to provide a plurality of plane surfaces as more clearly disclosed in the top plan view of Figure 2. The upper end of the shaft 7 extends considerably beyond the tank 5 and at a point spaced above the top of the tank, said shaft

is of square shape, as disclosed in Figure 1. 55 Loosely slideable upon the shaft beneath the squared end thereof is a collar 13 formed at its periphery with radiating pairs of spaced ears 14. Projecting between these ears are the inner flattened ends of axle bars 15, preferably four in number. The extreme inner ends of which carry cross pins 16, the ends of which are slideable in longitudinal slots 17 in said ears. Rigidly secured to the squared portion of the shaft 7 is a central collar 18 60 of a spider 19 that consists of a pair of cross arms, the outer ends of which are extended directly downwardly as at 20. A universal connection 21 is provided between the down turned ends of said cross arms of the spider 70 19 at the ends of said non-rotating axle bars 15 upon which are rotatably mounted flanged wheels 22 for engagement upon the previously mentioned wheel track 12. Slid- 65 able upon the squared portion of the shaft 75 17 beneath the rigidly attached collar 18 and the sliding collar 13 is a heavy weight 23, while arranged around the shaft between the weight and the lower collar 17 is an ex- 70 pansible coil spring 24. Extending upward- 80 ly from opposed points of this weight 23 are links 24 that are movable within slots 25 of two opposed arms of the spider 19. The upper ends of these links 24 are pivotally connected to levers 26—26, the inner ends of 85 which are pivoted to the upper end of the collar 18 of said spider while adjustably ar- 90 ranged thereon are governor weights 27—27. Obviously the purpose of this construction is to cause the weight 23 to force the spring 24 95 against the collar 13 for swinging the inner ends of the axle bars 15 in a downward direction so that pressure will be applied to the wheels 22 so that the same will positively hug the track 12 during the rotation of the same upon the track.

Also arranged around the tank 5 beneath the track 12 is a metallic ring 28 for the purpose of providing a circumferential shelf. Mounted upon this shelf is a plurality of air compressor cylinders 29 of a number complementary to the number of plane surfaces of the track 12. Rectilinearly movable within each cylinder 29 is a piston 30, while leading from the bottom of each cylinder is an 100 exhaust pipe 31 in association with which is an inlet and exhaust check valve 32 and 33, respectively, the exhaust check valve 32 open-

ing into the interior of the tank 5 as clearly disclosed in Figure 1.

Rigidly secured to each plane surface of the track 12 of the center thereof is a vertical 5 guide plate 34 within which is slidably mounted a piston actuating plate 35, the upper edge of which is tapered as clearly disclosed in Figure 4, which tapered edge normally projects above the edge of the rail 12 10 so as to be encountered by the wheels 22 as the same pass thereover. The lower end of each plate 35 is operatively connected to the respective piston rod 36 of the piston 30. Encircling each rod between the cylinder and 15 the plate is an expansible coil spring 37 for the purpose of returning the plate 35 to the position disclosed in Figure 4, after the same has been depressed by the action of the wheels passing thereover.

20 Each plate 35 is formed with a longitudinal slot 39 through which projects a pin 40 and upon the outer end of which is mounted a counterbalancing disc 41 suitably weighted at one point as generally suggested 25 by the disclosure in Figure 1. Eccentrically connected to this disc and the lower end of the wheel actuated plate 35 is a pitman 42 for causing the rotation of the disc during the reverse movement of the plate 35, the 30 same being for the purpose of counterbalancing the action of the plate during its operation.

In view of the foregoing description when considered in conjunction with the accompanying drawings it will at once be apparent that I have provided a highly novel, simple, and efficient air compressor that is well adapted for all the purposes heretofore designated, even though I have herein shown 35 and described the invention as consisting of certain detail structural elements, it is nevertheless to be understood that some changes may be made therein without effecting the spirit and scope of the appended claims.

45 Having thus described the invention, what I claim is:—

1. In an air compressor of the character described, a closed storage tank, a plurality of air compressor pumps arranged around 50 the exterior of the tank and including vertical piston rods, said pumps having communication with the interior of the tank, a track supported by the tank, wheels movable upon the track, means associated with the 55 pump pistons for engagement above the track so as to be encountered by the wheels to depress the pump piston, means for returning the piston, a drive shaft operatively connected with said wheels extending concentrically through the tank and drive 60 means for said shaft remote from the tank.

2. In an air compressor, a closed storage tank, a track rail arranged circumferentially around the tank and supported thereby, a 65 plurality of air compressor pumps also ar-

ranged around the tank beneath said rail and having communication with the interior of the tank, said pumps including vertically projecting piston rods, means attached to the upper ends of the rods for engagement 70 slightly above the upper edge of the track, means for normally maintaining said means in such position, and a rotating unit including wheels for engagement upon the track and for engagement with the pump rod 75 associated means for depressing the pump piston each time the wheels pass thereover, automatic means for returning the pump pistons to initial position, and means for causing the rotation of said unit. 80

3. In an air compressor, a closed storage tank, a track rail arranged circumferentially around the tank and supported thereby, a plurality of air compressor pumps also arranged around the tank beneath said rail 85 and having communication with the interior of the tank, said pumps including vertically projecting piston rods, means attached to the upper ends of the rods for engagement slightly above the upper edge of the track, 90 means for normally maintaining said means in such position, and a rotating unit including wheels for engagement upon the track and for engagement with the pump rod associated means for depressing the pump piston each time the wheels pass thereover, 95 automatic means for returning the pump pistons to initial position, means for causing the rotation of said unit, and a governor operatively connected to said unit adapted to 100 automatically force the wheels into positive engagement with the track.

4. In combination, an air compressor tank, a track arranged thereabout, wheels adapted to travel on the track, a drive shaft extending vertically through the tank, axles for the wheels extending radially thereof, operating means for the shaft, a plurality of pumps operatively engaged by the wheels, a weight resiliently supported at the upper 110 end of the shaft adapted to have its force distributed to the wheels and a governor controlling the distribution of the weight with respect thereto. 115

5. In combination, an air compressor tank, a track arranged thereabout, wheels adapted to travel on the track, a drive shaft extending vertically through the tank, axles for the wheels extending radially thereof, operating means for the shaft, a plurality of pumps operatively engaged by the wheels, a weight resiliently supported at the upper 120 end of the shaft adapted to have its force distributed to the wheels, a governor connected with the weight and the wheels adapted to control the distribution of the weight thereon and means for adjusting the governor. 125

6. In combination, an air compressor tank, a circular track supported thereby and 130

extending thereabout, wheels adapted to travel on the track, a shaft extending vertically through the tank, axles for the wheels extending radially therefrom and operatively connected to the upper end of said shaft, a weight for the wheels adapted to insure the positive engagement thereof with the rails, a governor adapted to control the force applied by the weight, a plurality of

pumps carried by the tank and having connection therewith, trips attached to the rails operatively connected to the pumps and engageable by the wheels for operation thereof and drive means for the shaft connected to the lower end thereof.

15

In testimony whereof I affix my signature.

THEODORE A. MATHEWS.
